UNITED STATES PATENT OFFICE.

CHRISTOPHER F. CODA, OF DETROIT, MICHIGAN, ASSIGNOR TO ART STOVE COMPANY, OF DETROIT, MICHIGAN, A CORPORATION OF MICHIGAN.

FIRE-POT.

No. 918,812.

Specification of Letters Patent.

Patented March 2, 1909.

Application filed March 28, 1908. Serial No. 423,942.

To all whom it may concern:

Be it known that I, CHRISTOPHER F. CODA, a citizen of the United States of America, residing at Detroit, in the county of Wayne 5 and State of Michigan, have invented certain new and useful Improvements in Fire-Pots, of which the following is a specification, reference being had therein to the accompanying drawings.

10 The invention relates particularly to a fire port for stoves or furnaces of the slotted type wherein a plurality of flues or air passages extending vertically of the fire pot are provided to admit the air for supporting 15 combustion within the interior, and the invention consists in the novel construction of a fire pot of this type; further, in the peculiar construction, arrangement and combination of the various parts; and, still further, 20 in certain details of construction as will be more fully hereinafter set forth.

In the drawings,—Figure 1 is a vertical central section through a fire pot embodying my invention; and Fig. 2 is a sectional perspective view.

25 A represents a fire pot, consisting primarily of an inclosing wall B forming the body, provided with an air chamber C at its upper end and with a plurality of circumferentially arranged vertically-extending air passages D leading from the bottom of the fire pot upwardly to and communicating with the air chamber, as plainly shown in Fig. 1. Preferably the exterior of the inclosing wall is provided with a series of longitudinally-extending thickened portions or ribs E, and these ribs are made hollow so as to form the air passages described.

30 Any form of air chamber may be employed at the top of the fire pot, but the preferred construction is as shown in Fig. 1, the walls of the chamber being formed by an annular laterally-extending integral flange F upon the upper end of the fire pot and a 35 curved annular section G adapted to be seated upon the outer portion of the flange F and within a groove H in the extreme top portion of the body section, as indicated.

I represents a suitable damper-controlled 40 draft opening for the ring or air chamber, and J designates the usual apertured supporting ears at the bottom of the fire pot.

45 As shown in Fig. 1, the vertically-extending flues open inwardly, as indicated at K, 50 within the interior of the fire pot, and these

55 lateral openings extend from the lower edge of the latter for a considerable distance upwardly, terminating preferably at a point substantially midway between the top and bottom, leaving an imperforate zone L about 60 the upper portion of the fire pot. The lateral openings, as well as the vertical flues, taper, gradually increasing in size from their upper ends to the lower so as to permit any ashes or other matter that may accumulate 65 therein to be readily discharged.

The style of fire pot described is adapted for use in connection with a substantially closed gate, and in use the air supply is derived from the air chamber C. The air is 70 first heated within the air chamber, and then passes downwardly through the flues within the interior of the fire pot through the lateral openings described. The parts are 75 so proportioned that the air is fed circumferentially about the burning fuel only, the green fuel being entirely above the lateral openings and surrounded by the imperforate zone, which constitutes a coking section for the unburned fuel. Before the 80 latter works down into the slotted section of the fire pot it has become sufficiently coked to prevent the entry of particles within the slots, thus choking the air passages, and the consequent obstruction of the air supply 85 is obviated.

What I claim as my invention is,—

1. A single-piece cast metal fire pot having a circumferentially arranged series of vertical air flues or passages formed in its 90 inclosing wall, each passage extending vertically from the lower to the upper portion of the wall and laterally, to permit the discharge of air within the fire pot, for substantially half its length from the bottom upward, the upper portion of the inner surface of the wall being imperforate and forming a coking section for and entirely surrounding the green fuel.

2. A fire pot, provided with a series of 100 vertical air passages formed in its inclosing wall, and having its inner fuel-contacting surface divided into an upper imperforate coking section, adapted to surround the green fuel, and a lower slotted section, the 105 slots communicating with the vertical air passages.

3. A fire pot, comprising an inclosing wall, having an annular air chamber at its upper end and provided with a circumfer- 110

tial series of vertical air passages extending from the lower edge of the fire pot to and communicating with the air chamber, the inner surface of the wall downwardly from the air chamber to near the middle of the fire pot being imperforate, forming a coking section for and surrounding the green fuel, and the remainder of said surface being slotted, the slots having communication lat-

erally throughout their length with the vertical air passages.

In testimony whereof I affix my signature in presence of two witnesses.

CHRISTOPHER F. CODA.
